UNITED STATES PATENT OFFICE.

ANNA K. MAY, OF PHILADELPHIA, PENNSYLVANIA, ASSIGNOR TO WILLIAM H. McCALLUM AND IRVING McCALLUM, OF SAME PLACE.

DESIGN FOR CARPET FOR RAILWAY-CAR SEATS.

SPECIFICATION forming part of Design No. 31,880, dated November 21, 1899.

Application filed October 26, 1899. Serial No. 734,886. Term of patent 3½ years.

To all whom it may concern:

Be it known that I, ANNA K. MAY, a citizen of the United States, residing at the city of Philadelphia, in the county of Philadelphia and State of Pennsylvania, have invented and produced a new and original Design for a Carpet for a Railway-Car Seat, of which the following is a specification, reference being had to the accompanying drawing, forming part thereof.

The leading feature of the design comprises a generally rectangular ground well covered with small ornamental figures and having upon three of its sides a border.

In the drawing, 1 is the generally rectangular ground well covered with small Oriental

figures, and 2 is the border arranged around three sides of the ground and consisting of scrolls 3, which break into the ground and are arranged inside of a lattice-work 4.

Having described my invention, what I claim as new, and desire to secure by Letters Patent, is—

The design for a carpet for a railway-car seat, substantially as shown and described.

In testimony whereof I have hereunto signed my name.

ANNA K. MAY.

In presence of—

GRACE B. HURLBUT,
W. J. JACKSON.
